UNITED STATES PATENT OFFICE.

EMIL LAWRENZ, OF DETROIT, MICHIGAN.

CUTTER.

1,073,254.

Specification of Letters Patent. Patented Sept. 16, 1913.

Application filed May 31, 1912. Serial No. 700,575.

To all whom it may concern:

Be it known that I, EMIL LAWRENZ, a citizen of the United States, residing at Detroit, in the county of Wayne and State of Michigan, have invented certain new and useful Improvements in Cutters, of which the following is a specification.

This invention relates to cutters and more especially to that class thereof which may be utilized in connection with last-turning lathes, and it has for one of its objects the provision of a cutter-head comprising a series of cutters for acting upon the block to be turned in such a manner as to cut away the superfluous material of the block to a great extent so that another cutter-head comprising one or more finishing cuts, may then be enabled to reduce the block to substantially finished size and shape.

20 The invention has, furthermore, for its object the provision of such a primary cutter-head in which a series of knives are held and positioned so as to cut the stock in adjacent lateral planes relatively to the rotation axis of the block or work, and so that each knife will remove only a comparatively small amount of the block longitudinally of the axis thereof.

25

A further object of the invention resides in novel means for bringing same into required adjustment as to radial distance from a cutter axis, and in improved means for holding the knives in adjusted positions.

Further objects of the invention will hereinafter appear and be particularly defined in the claims.

The invention has been clearly illustrated in the accompanying drawings in which similar characters denote similar parts and

40 in which—

Figure 1 is a face view of a cutter-head embodying my invention. Fig. 2 is an edge view thereof, partly broken away. Fig. 3 is a top view of one of the knives. Fig. 4 is a cross section on line 4—4 of Fig. 1.

Briefly stated the present invention is designed to avoid the objections heretofore met in devices of this character, in the generally adopted forms of which each knife 50 has to be filed in order to bring about the required adjustment when the cutting edge became worn. In machines of the character mentioned, the cutters are rotated at a very high velocity always, the outward pull on 55 the knives becomes a tremendous one, not only on account of the centrifugal force

which manifests itself upon each individual knife.

Referring now to the drawings, 10 denotes the cutter-head mounted upon the spindle 11 which constitutes part of the machine. Carried by the head 10, are a series of progressively operated knives 12^a, 12^b, 12^c, 12^d, and 12^e, each of which has its shank portion 13 seated within a groove 14 provided therefor in the head 10, this groove being slightly deeper than the shank of the knife and having its side walls milled away as indicated at 15 to receive a washer 16, which latter is thus held against slipping movement in the groove, and may be held against upward movement by a bolt 17 in screw-threaded engagement with the main body of the head 10 as shown in Figs. 2 and 4, it being understood that this bolt passes 70 through the shank 13 of the knife as for instance through an elongated aperture 18 so as to permit outward radial adjustment of each knife.

As above stated the knives are exposed to 80 a tremendous outward pull when in active operation, and for this reason means are provided whereby each knife, or rather the shank portion thereof, is firmly held against accidental displacement, these means consisting preferably of a pair of diametrically opposite teeth 19 provided on the under-side of the washer 16 and adapted to engage any one of a series of lateral grooves 20 provided in the upper surface of each 90 knife shank which is furthermore fitted closely between the side-walls of the groove 14 of the cutter-head. From the above it will be clearly seen that each knife is positively locked in position on the head.

In the present instance the cutter-head is rotatable in the direction of arrow *a*, and the knives 12^a, 12^b, 12^c, 12^d, 12^e, become successively operative upon the work in the order named, *i.e.* in the longitudinal 100 axial travel of the cutter-head relatively to the head, while at the same time they cut progressively deeper into the end of the block, as is clearly indicated in Fig. 2 in which the block or work is indicated by *W*, 105 and the several cuts produced by the knives are indicated by the several lines generally denoted by *c*.

It is to be understood that the particular formation of the knives may be changed according to various requirements, and also that they may be seated relatively to the

center in different ways so as to fulfil the conditions to be met. In the present instance the knives are so set, that their center lines are slightly in advance of a line *e* drawn in parallelism thereto through the center of the head 10. Other changes may also be made in the particular construction of some of the parts, without departing from the spirit of the invention.

10 I claim:—

1. The combination with a head having a substantially radial groove, of a knife blade having a shank of less depth than the groove, a washer sidewise overlapping the shank and in locked engagement with said shank and intersecting a side wall of said groove, and means for drawing said washer and the knife blade into firm contact with the head.

2. The combination with a head having a substantially radial groove, of a knife having a shank fitted for longitudinal movement in said groove and having a thickness less than the depth of said groove, a series of indentations in the outer face of said shank, a washer having in its under-side a projection adapted to enter any one of said indentations, said washer also intersecting the sides of and seated in said groove, and means for drawing said washer and shank into tight engagement with the head.

25 In testimony whereof I affix my signature in presence of two witnesses.

EMIL LAWRENZ.
